CONTROL APPARATUS

Alfred Leslie Pfeil, Cleveland, Ohio

Application November 26, 1934, Serial No. 754,835

20 Claims.

(CL. 219—8)

This invention relates to an electric apparatus, and particularly to a control means for governing the speed of a propulsion machine for an electric current generator. The illustrated embodiment 5 is particularly adapted to serve in connection with arc welding apparatus but is not necessarily limited to this use.

Apparatus of the type above outlined is already known and it is old to control the speed and power 10 of the propulsion means in accordance with, i. e. in proportion to, the electric current used under varying conditions. The present improvement in said type of apparatus relates both to an improved arrangement for governing the motor or 15 propulsion machine; to a new device specifically adapted for controlling an internal combustion motor in connection with generating electric current for various purposes, and still more specifically to a device for affecting the speed and/or 20 power of the propulsion machine for an electric generator in accordance with the electric power requirement for arc welding.

The general object of the invention is to provide an electric apparatus including an electric 25 power generator and propulsion machine therefor, wherein the power output of the propulsion machine is varied in direct proportion to the electric current requirement.

A specific object is to provide a control for an 30 internal combustion engine coupled with an electric generator for welding sets e. g. wherein the engine vacuum is utilized directly for quickly increasing the speed and power of such engine from idling speed to the desired or required speed for 35 generating the required current.

Another object is to provide an improved control for an internal combustion engine driven electric current generating set wherein deceleration 40 of the engine to idling speed is automatically delayed a desired predetermined controllable period in accordance with the use of the generated current.

Another object is to provide an improved automatic control device of the type above outlined, 45 operable in connection with either A. C. or D. C. generators.

A further object is to provide a control for the 50 speed or power of a propulsion machine for an electric generator which will be operable electrically and electro-magnetically by the use of a very small current.

A further object is to provide a control for the 55 propulsion machine which will not be deleteriously affected by heat emanating from the pro-

pulsion machine in case the latter is an internal combustion motor.

A further specific object is the provision, in an internal combustion engine driven generator set, of a simple, compact and unitary electrically 5 and pneumatically actuated control for governing the speed of the engine.

Still another object is to provide a more simple inexpensive and compact automatic control for internal combustion engine driven arc welding 10 sets.

A further object is to provide an electrically operated vacuum release for apparatus of the type described, wherein the parts are reduced to substantially a minimum number and size. 15

A further object is to provide a unitary control device for an internal combustion motor used as the propulsion means for driving an electric generator, wherein the likelihood of disarrangement of the device, due to shock or continued vibration, is materially reduced. 20

The novel features of the invention will become apparent from the following description relating to the accompanying drawings. The essential novel characteristics are summarized in 25 the claims.

In the drawings: Fig. 1 is a side elevation of the control apparatus mounted on an internal combustion engine, a small portion of the latter being shown; Fig. 2 is a sectional view as indicated on Fig. 1; Fig. 3 is a sectional view as indicated on Fig. 2 and Fig. 4 is an electrical and 30 mechanical diagram showing one use for the invention.

Referring further to the drawings, 1, in Figs. 35 1 and 2, indicates a portion of an internal combustion engine cylinder block, the conventional intake manifold of which is shown at 2. The carburetor for such engine is conventionally shown at 3, this being connected to the intake 40 manifold by flange pipes 4 and 5 between which a unitary valve control apparatus, designated generally 10, is interposed. This, as shown, includes a valve housing or body member 11 with a butterfly valve 12 on a shaft 12', the central 45 opening 13 of the housing 11 being aligned with the engine intake fuel ducts of the pipes 4 and 5.

The butterfly 12 is similar to the valve of the usual engine throttle mechanism. The usual carburetor, butterfly valve, control levers and control rods are not shown, and these may be connected to a conventional mechanical governor in the usual fashion for controlling the engine 50 operating speed under load without affecting the control unit hereof. The butterfly shaft 12' ex- 55

tends outwardly from the body 11 into a hollow frame 15 positioned adjacent the body 11, as shown in Figs. 1 and 2 and suitably secured thereto in conventional fashion (not shown). The 5 shaft has a gear sector 16 thereon, the teeth of which mesh with rack teeth on a sliding bar 17 carrying a piston 20 in a cylinder 21, (to be later more fully described) the rack bar being slidably mounted in the frame 15. A suitable spring 10 is, as shown, associated with the sector to normally close the butterfly. This closing operation moves the bar 17 toward the left (Fig. 2). As shown, the spring 18 surrounds a hub formation on the body 11 and bears at one end against 15 the stop 19, the opposite end of the spring being secured in suitable fashion as at 19' (Fig. 3) to the gear sector.

As shown in Figs. 2 and 4, suitable means are provided to adjustably limit the closing movement of the valve 12 to regulate the motor idling speed; this means, as shown, comprising a screw 17a adapted to engage the piston 20, the screw being threaded into a flange portion 15' of the frame 15, the flange forming an end wall of the cylinder 21 above mentioned.

The cylinder for the piston 20 is part of a body member 22 attached to the housing 11, as by suitable bolts 23, one being shown in Fig. 2. The right hand end (Fig. 2) of the cylinder 21 is arranged for connection by suitable passages with the suction side of the engine, so that engine vacuum opens the butterfly valve 12.

It will be seen from the drawings, particularly Fig. 2, that the necessary vacuum passages are compactly formed in or rigidly mounted on the body members 11 and 22 thereby obviating the necessity for separate tubes and couplings such as ordinarily used and which are necessarily expensive and subject to leakage and breakdown due to crystallization of the metals composing them under continued stresses set up by the unavoidable vibrations of the engine. The vacuum connections between the cylinder 21 and the fuel intake passage of the motor are arranged 45 as follows:

Further referring to Fig. 2, the body 11 has a short bore 25, in one end of which is mounted a short tube 26 (position further indicated in Fig. 1) having its open end lying within the fuel passage to the motor, said open end being directed toward the intake manifold as illustrated. The disposition of the tube 26 is such that passage of air and vaporized fuel from the carburetor to the intake manifold constantly tends to evacuate the bore 25. Aligned with and in sealed relation to the bore 25 is another bore 27, the right hand end of which, as shown may be conically formed to provide a valve seat 27'. The seat is normally closed by engine vacuum operating on a freely axially movable valve plug 28 supported as will be presently described, the plug having at its inner (left hand) end a valve seating surface complementary to the seat 27'.

Leading from the seat surface 27' to the cylinder 21 adjacent the outer (right hand) face of the piston is a small duct 30 which is normally closed by the plug 28 when the plug closes the bore 27, but which, when the plug is withdrawn from its seat, opens communication between the engine intake passage 13 etc. and the cylinder 21 through bores 25, 27 and 30, whereupon the bar 17 is withdrawn with respect to the butterfly shaft, the sector thus opening the butterfly valve.

The valve plug 28 is the armature of a solenoid 31, the latter being tightly sealed in a cylindrical

enlarged space 32 at the outer end of the body member 22. At least a portion of the plug is therefore made of soft iron. The plug, as shown, has free sliding clearance in a suitable tube 33 forming the center of the solenoid 31, the tube 33 having at its outer end a short pipe 34 with an axial bore forming an air inlet, that is, communicating with the outside atmosphere. When the plug is withdrawn from its seat by the action of the solenoid the outer end of the plug seals this air inlet as illustrated in Fig. 2. A suitable arrangement of cap for supporting the outer end of the pipe 34 and suitable electric terminals for the extremities of the solenoid winding is shown at 35. This cap also preferably supports an air 10 cleaning body of suitable material as at 36 for removing foreign matter from outside air admitted to the inlet pipe 34. The air cleaner may 15 comprise any materials conventionally used for this purpose.

The air inlet pipe is communicated with the outer end of the cylinder 21, partly through the plug clearance of the tube 33 and partly through a duct 38, 39' communicating the cylinder 21 with the enlarged space 32. This duct 38, 39' 20 is controllably restricted as by a needle valve 40 so that air from the pipe 34 is admitted to the cylinder 21 at the desired speed to delay the return movement of the piston in its operation of closing the butterfly valve and slowing down 25 the motor to idling speed as will be later more fully described.

The manner in which the solenoid 31 is energized will be more fully explained in connection with Fig. 4, but it will be noted that when the 35 plug is in the position shown in Fig. 2 cutting off the air inlet 34, engine vacuum is directly communicated with the cylinder 21 through passages 25, 27 and 30 and the valve is opened quickly; maximum engine speed being thereby quickly attained. On the other hand, when electric current is cut off from the solenoid 31, engine vacuum immediately acts through the plug 28 to close both the passages 27 and 30 and simultaneously to open the right hand end of the cylinder 21 40 to the outside atmosphere through the pipe 34 etc. and controllable duct 38. The simplicity of the arrangement whereby a single member (28) functions as the plunger of the solenoid, the atmosphere shutoff and inlet valve and the vacuum 45 release and shutoff valve is to be particularly noted. The restriction, needle valve 40 e. g., in the duct 38 necessary to accomplish the desired slow return movement of the piston to close the butterfly valve may be set after adjustment 50 by a lock nut 41.

One of the reasons for the success of this device is that even though the unitary device is fairly close to the hot exhaust manifold or in an atmosphere of very warm air or other gases prevailing near internal combustion engines, the unitary device is exceedingly cold especially at the valve body 11 due to the heat absorption effect of fuel vapor mixture as it expands into the intake manifold. The unitary metallic assembly of the 60 device herein shown and described permits this heat absorption characteristic to quickly withdraw heat generated in the coil 31 due to currents passing through 31 or heat radiated or conducted to the unitary assembly from adjacent hot parts of 65 the apparatus on or near which the unitary assembly may be placed.

Thus: (a) the coil 31 may be operated at much higher densities, i. e. higher heating internal losses with consequent saving in coil cost and 70 75

increase in coil effectiveness; (b) the cylinder wall contacting material of the piston 20 is not subject to disintegrating effects of heat and hence has longer life with uniform performance due to retaining its original qualities; and (c) the lubricating film on the inside of the cylinder wall 21 retains its lubricating qualities for a long period without attention.

Referring now to the electric diagram, Fig. 4, 10 wherein an exemplary use on a direct current arc welding set is diagrammatically shown, 50 indicates conventionally a generator which it is assumed is driven by the internal combustion motor e. g. through any suitable coupling. The generator 15 may have a series field 53 connected therewith through a main lead 52, a commutating field 54 and a series inductive stabilizing device 55. The 20 series inductive stabilizing device is in any event an inductive winding, which may take the form of an auxiliary stabilizing inductive field winding inside of the generator, or an inductive winding in series with but externally of the generator itself. The work to be welded indicated at "W" may be connected as by a line 51 to one side of the generator 25 and the electrode or welding wire "E" to 55 as by a line 57.

The solenoid coil 31, in order that this may be made very small and operate without being appreciably heated, is connected in shunt arrangement with one or more of the windings 53, 54 30 and 55, and the solenoid 31 initially operates to draw the plug valve 28 into the coil by reason of the relatively large surge of current due to the inductive drop which occurs across the winding 35 to which the solenoid is connected, upon the establishment of the welding circuit e. g. through said winding or windings, and the solenoid continues to retain the plug 28 by reason of the small current due principally to the impedance voltage 40 drop across the coil or coils 53 etc. In arc welding, an impedance voltage drop occurs sufficiently constantly to maintain the solenoid in operation due to constant fluctuations in the arc circuit caused by drops of metal crossing the arc and 45 creating in the neighborhood of 900 to 1500 short circuits per minute. The plug 28, (in event of using the apparatus for arc welding) is also maintained by the solenoid in withdrawn position by inductive drop across the inductive winding, due 50 to the ragged characteristics of the current, so long as the welding arc is maintained. As shown, one terminal of the solenoid is connected, as through line 58, with the lead 52 from the generator, and the other terminal (as shown in full 55 lines) to the line 57, as by line 59. Alternatively, said other terminal of the solenoid may be connected, as by line 59a (shown in broken lines) across only the series field or, by line 59b (similarly shown) across the commutating field. The 60 actual connections of the solenoid 31 with the welding e. g. current depends upon the impedance drop afforded by the selective inductive windings and the design of the coil 31.

It will be seen that whenever the electrode "E" 65 is applied to the work a high inductive drop occurs across the windings 53, 54 and 55, due to the rapid rise of welding current or rapid rate of increase of current (and magnetic flux proportional thereto) through said windings and, since the solenoid 31 is shunted across one or a selected combination of these windings, a sudden surge of current will pass through the coils of the solenoid thereby initially withdrawing the plug 28 from its seat 27. When the welding arc is fully established at "E" and "W" the current flow

through the solenoid 31 is, of course, considerably less, but nevertheless the flow is sufficient to hold the armature-plug 28, in the position illustrated in Fig. 2, and the engine will be maintained in the full load operating position since the valve 12 will be kept fully open by engine vacuum. Now, should the operator remove the electrode "E" from the work "W", breaking the arc, no current will then flow through the solenoid 31, the plug 28 will be released from the pull of the solenoid, and 10 the engine vacuum will immediately return the plug to initially seated position and the cylinder 21 will be again communicated with the air inlet tube 34 to relieve the vacuum therein. However, since the air passage 38 is greatly restricted, air 15 from the tube 34 will slowly leak into the outer end of the cylinder 21 and the plunger will be very gradually withdrawn by the spring 18 to a position such that the throttle valve 12 will be moved to the idling adjustment determined by the setting 20 of the screw 17a. Thus, while the engine will begin to slow down immediately upon disruption of the welding arc, the engine will nevertheless be kept up to nearly maximum speed for an appreciable time such that if the welding arc is 25 broken only for a period of a few seconds while the operator adjusts the electrode and then the arc is reestablished, there will be no appreciable slowing down of the engine from full current generating speed. 30

In some instances it is desirable to regulate the acceleration of the engine, in which case a reservoir (not shown) may be connected with the passage 38' at the position indicated at 38'', Fig. 2, which reservoir as well as the cylinder 21, when 35 filled with air at atmospheric pressure, must be evacuated through the passages 30, 27 etc. before the valve 12 is opened to full motor speed position. The capacity of the reservoir is determined by the maximum acceleration delay 40 desired and the delaying action may be regulated by any suitable valve operating to restrict or close the passage from the reservoir to the cylinder 21. Acceleration might also be controlled for 45 more gradual operation by adjustably restricting the passages 25, 27 or 30 e. g., say in the manner of controlling the passage 38 for engine slow down delay.

In the case of providing such reservoir in connection with—say the passage 38', a longer delay 50 would ordinarily obtain before the engine slows down, upon rupture of the welding e. g. circuit, because the reservoir will also be subject to engine vacuum during load speed of the engine and part of the air admitted through the passage 38 55 will pass into the reservoir. Accordingly, the needle valve is adjusted for less restriction of the passage 38 for a given slow down delay when such reservoir is used in open communication 60 with the piston cylinder.

In view of the above description it is apparent that the apparatus is not limited in use to any particular field of work, such as arc welding for example. Moreover, its use is not limited to direct current generating apparatus. In case the 65 generator is A. C. (not illustrated) the coil 31 may be in series with the generator line or may be connected across a small inductance in the generator line (not illustrated).

In general, the apparatus and modifications 70 of the same are useful wherever it is desired to drive the propulsion means of an electric generator at one speed for one condition of load and to drive the propulsion means at another or different speeds for other or different conditions of 75

load. The generated current may be used to drive motors or to perform practically any other function that may be performed electrically.

I claim:

5. 1. In an electric apparatus, an electrical generator, a propulsion apparatus for the same, a means operable by an effect created by the motivating cause of conveyance of input to said propulsion apparatus to accelerate said propulsion 10 apparatus and an electrically operable means connected electrically with the output circuit of said electrical apparatus and actuating the aforesaid means upon establishment or disestablishment of the said output circuit.
15. 2. In an electric apparatus, an electric generator, a propulsion apparatus for the same, means operated by an effect created in proportion to the rate of conveyance of input to said propulsion apparatus, said means, upon actuation, being 20 adapted and arranged to accelerate the propulsion apparatus, and electrically operable means connected electrically with the output circuit of said electric generator, the last named means being arranged to actuate the first named means 25 consequent upon a predetermined change in the condition of the output circuit.
30. 3. In an electric apparatus, an electric generator, an internal combustion engine for driving the same, means operable by engine vacuum to initiate acceleration of the engine, and electrically operable means electrically connected with the output circuit of the generator, said last named means being arranged to actuate the aforesaid means upon a predetermined change in the 35 electrical condition of said output circuit.
40. 4. In electric apparatus, an electric current generator, an internal combustion engine for driving the same, means operable by engine vacuum to initiate acceleration of the engine, and electrically operable means electrically connected with the output circuit and actuating the aforesaid means upon establishment of the output circuit.
45. 5. In an electrical apparatus, an electrical generator, an inductive coil connected with the output circuit of the generator, a propulsion apparatus for the generator and means for accelerating or decelerating the same, said means being operated by the motivating cause of conveyance 50 of input to the propulsion means, an electromagnetically operable device arranged to initiate the operation of the aforesaid means, said device being electrically connected in shunt relation with said inductive coil and being operated by the inductive drop thereacross when the output circuit 55 is established.
60. 6. In an electrical apparatus, an electric generator, an inductive means forming part of the generator windings connected with the output circuit of said generator, an internal combustion engine for driving the generator, a valve for controlling the speed of the engine, engine vacuum operated means to operate the valve to accelerate the engine, and an electro-magnet arranged to 65 actuate the valve operating means, the magnet being electrically connected with the said output circuit in shunt relation with said inductive means and being operated by the inductive drop thereacross when the output circuit is established.
70. 7. In an electric apparatus, an electric generator, an internal combustion engine for driving the generator, means operated by engine vacuum arranged to accelerate the engine, said 75 means including a passage normally subjected to

said engine vacuum and a valve controlling said passage to render said means effective, an electric solenoid arranged to actuate the valve, said generator having a series field in the output circuit thereof and the solenoid being connected in shunt relation with said field.

8. In an electrical apparatus, an electric generator and output circuit including inductive means, an internal combustion engine for driving the generator, control means responsive to engine 10 vacuum to accelerate the engine, electrically operable means connected with the output circuit in shunt relation to the inductive means, and means whereby the electrically operable means renders the control means initially operative.

15. 9. In an electric arc welding apparatus of the type comprising a welding current generator and welding circuit including inductive means and an internal combustion engine for driving the generator, the combination therewith of control 20 means responsive to engine vacuum to accelerate the engine and electrically operable means connected with the welding circuit in shunt relation to the inductive means, said electrically operable means rendering the control means initially 25 operative upon establishment of the welding arc.

10. In an electrical apparatus, an electric generator having an output circuit, an internal combustion engine for driving the generator, a vaporized fuel inlet for the engine and a valve for controlling said inlet, means actuated by engine 30 vacuum arranged to operate the valve to control the engine, said last named means including a passage from said means to a portion of said inlet, a vacuum control valve to normally seal 35 said passage, electrically operable means electrically connected with the output circuit and cooperating with the valve to unseal the passage on a predetermined condition of the output circuit, and means for admitting air to said vacuum 40 operated means under sufficient pressure to relieve the vacuum, the vacuum control valve automatically blocking the air admitting means when unsealing said passage as aforesaid and opening said air admitting means when in the passage sealing position.

11. In an electrical apparatus, an electric generator, an internal combustion engine for driving the generator, said engine having a conduit forming a vaporized fuel inlet passage between the 50 carburetor and combustion space of the engine, a valve controlling said passage to govern the speed of the engine, a piston and cylinder unit, the piston being operatively connected with the valve, duct means to communicate the cylinder 55 with the fuel inlet passage in such manner that engine vacuum operates the piston in a direction to open the valve to accelerate the engine, electrically operable means connected with the output circuit of the generator and operated by a change 60 in said output circuit, means associated therewith to control the duct means to thereby control the operation of said engine vacuum on the said piston, said piston and cylinder unit being supported in intimate metallic contact with said 65 fuel inlet conduit, whereby the unit will be cooled by expansion of the vaporized fuel in said inlet passage.

12. In an electrical apparatus, an electric generator, an internal combustion engine for driving the same, said engine having a conduit forming a fuel inlet passage, a vacuum operated device and means associated therewith to control the speed of the engine, said device comprising a unitary metal body having the necessary fluid 75

passages to render the device operative pneumatically, formed substantially entirely therein in compact arrangement, said passages including a duct communicating with the said fuel passage, 5 and electrically responsive means arranged to render the device initially operative, said means including an electromagnet connected with the output circuit of the generator and operated by a predetermined change in the condition of said 10 circuit.

13. The combination with a generator, an engine for driving the generator, and a control mechanism actuated by a mechanical energy effect created by the engine for accelerating and 15 decelerating the engine, of means operated in response to increases in the generator output to directly associate said mechanism and energy effect for accelerating the engine, and operated in response to a reduction or cessation of output 20 to initially disassociate said mechanism and energy effect and control the rate of disassociation thereof.

14. In an electric apparatus, a generator having an output circuit, a propulsion device, a speed 25 control mechanism for accelerating and decelerating the propulsion device and operable by direct application of a mechanical energy effect created by the propulsion device, control means for controlling the application of said energy to the 30 mechanism, means operable consequent upon establishment of the output circuit to initially actuate said control means for operatively associating said mechanism directly with said energy effect, said second named means operating consequent upon the maintenance of normal flow of 35 current in the circuit to maintain said association, said control mechanism operating to quickly accelerate the propulsion device when initially associated and maintaining the accelerated speed 40 during continuance of said association, said control means operating consequent upon a predetermined reduction of the flow of current in the output circuit below normal to initiate disassociation of said energy effect and mechanism after 45 said initiation, whereby said mechanism may gradually decelerate the propulsion device.

15. In an electrical apparatus, a generator, an engine for driving the generator and for creating a differential in fluid pressure effect at a given 50 source, control means operable by a differential in fluid pressure to accelerate the engine, and means operated by an increase in the generator output to initiate direct operative association of said control means and pressure source for accelerating said engine and operated by a continuance of generator output to maintain said direct association.

16. In an electric apparatus, an electric current generator having an output circuit, a power 55 device for driving the generator, means to accelerate and decelerate the power device including means acting with substantially constant force tending to effect deceleration, electromagnetically operable means connected to the output circuit

and acting on the first-named means to initiate the accelerating operation thereof when the circuit is closed and to render the constant force means effective to decelerate the power device when the circuit is opened, and pneumatically operated means acting in opposition to the constant force means to retard the decelerating operation. 5

17. In an electric apparatus, an electric current generator having an output circuit, a power device for driving the generator, means to accelerate and decelerate the power device including 10 constantly acting means tending to effect deceleration, electromagnetically operable means connected to the output circuit and acting on the first-named means to initiate the accelerating 15 operation thereof when the circuit is closed and to render the constantly acting means effective to decelerate the power device when the circuit is opened, and means initiated in its operation by the electromagnetically operable means during 20 its said operation on opening the circuit to retard the decelerating operation.

18. In an electric apparatus, an electric current generator having an output circuit, an internal combustion engine for driving the generator, 25 a valve controlling fuel feed to the motor, means constantly tending to close the valve, a pneumatically operable device connected to the suction side of the engine arranged to open the valve, electromagnetically operable means connected to the output circuit and arranged to initiate and maintain operation of the pneumatically operable device whenever the said circuit is closed and to render the same inoperative when the circuit is opened, and means actuated by the electromagnetically operable means during its said 30 operation on opening the circuit to retard the operation of the valve-closing means.

19. In apparatus of the class described, an internal combustion engine, means to control the speed of the engine and vacuum operated means to actuate said control means in a manner to accelerate the engine, said vacuum operated means having a pneumatic connection with the suction side of the engine, a control valve for said 45 vacuum operated means, an electro-magnet operatively connected with the valve to open the same when energized and render the vacuum operated means effective to perform the aforesaid function, said valve being automatically returned to closed position by said engine vacuum when the electro magnet is deenergized.

20. In apparatus of the class described, an internal combustion engine, a fuel introduction conduit therefor and speed control valve in the 55 conduit, vacuum operated mechanism to control the valve to move the same from engine idling position to load position, electromagnetically operable means to initiate operation of the vacuum operated mechanism and an adjustment device 60 associated with said mechanism to vary the idling speed of the engine.

ALFRED LESLIE PFEIL.
